AIR CONDITIONING APPARATUS AND
METHOD

Marion F. Knoy, Long Beach, Calif.

Application December 6, 1937, Serial No. 178,435

4 Claims. (Cl. 183—120)

My invention relates to air conditioning apparatus, more particularly such apparatus utilizing changes in the state of a circulating fluid heat-transfer medium, and is directed to an improved form of such apparatus effective for temperature and humidity control at all seasons of the year.

In air conditioning apparatus of the type involved here, a suitable fluid in a flow circuit is alternately vaporized and condensed to serve, in effect, as a pump for transferring heat from one zone to another. One of the objects of my invention is to provide a reversible heat-transfer cycle whereby the fluid may be either vaporized or condensed at a selected point in the circuit.

The outdoor atmosphere constitutes a huge reservoir into which considerable quantities of heat may be discharged, or from which considerable quantities of heat may be withdrawn, without appreciable effect on its temperature as a whole. An object of my invention is to provide a reversible means whereby at one season of the year heat may be transferred from an indoor body of air to this outdoor reservoir, and, at another season of the year, transferred from the outdoor reservoir to the indoor body of air. In this latter function of transferring heat to an interior body of air, it is my further purpose to generate heat mechanically by electrically actuated means at considerably less expense and with considerably greater efficiency than is possible by the usual procedure of passing an electric current through a resistor.

Broadly described, one aspect of my invention comprises the combination of a heat exchanger exposed to outdoor air, a heat exchanger exposed to indoor air, means providing a fluid course through the two heat exchangers for a suitable heat-transfer medium, a compressor connected with the fluid course for subjecting said medium to pressure, and means to reverse the direction of fluid through the fluid course.

One object of my invention is to arrange such a combination so that when the circulation is in one direction, one of the heat exchangers will be suitably supplied with the liquid medium to serve as an evaporator, the second heat exchanger being suitably drained of liquid medium to serve as a condenser, and when the circulation is in the opposite direction, the second heat exchanger will in turn be supplied with liquid medium to serve as an evaporator, and the first heat exchanger drained of liquid to serve as a condenser.

To meet the requirements of serving a plurality of indoor stations, it is my object to provide in one form of my invention a central heat exchanger exposed to outdoor air and a plurality of

dispersed secondary heat exchangers exposed to indoor bodies of air at the various stations, with the system arranged for supplying each heat exchanger with liquid when the heat exchanger functions as an evaporator and for draining the heat exchanger when it functions as a condenser.

In another form of my invention, it is my purpose to provide a self-contained unit of a portable character having one of its heat exchangers adapted for exposure to outdoor air and the other of its heat exchangers adapted for exposure to indoor air.

In the preferred form of my apparatus, I have the further object of providing a novel form of temperature control achieved by making the compressor responsive to the pressure in one side of the heat-transfer circuit.

In mild climates, my air conditioning apparatus by virtue of its reversible circulation alone will meet all seasonal requirements for temperature control of an indoor body of air. In more extreme climates where the outdoor temperature falls substantially below 40° F., circulation reversal of the heat-transfer medium may not always suffice to heat the indoor body of air to a comfortable temperature. With such exigency in mind, I may combine a combustion means with at least a part of the fluid course whereby the heat-transfer medium may serve as a means for conveying heat derived from fuel.

An important feature of the preferred forms of my invention is the provision of means such as a spray arrangement for wetting the exterior surface of one or more of the heat exchangers in the system. Among my objects of such provision are: To facilitate transfer of heat between the heat exchanger and the surrounding air; to wash the air; to control the humidity of the air; and to prevent frost formation on a heat exchanger functioning as an evaporator. An important advantage of such an arrangement is that the humidifying effect achieved may be regulated by varying the concentration of a solute in the spray liquid.

The forms of my invention herein described are characterized by the conception of interrelating the spray means associated with one heat exchanger with the spray means associated with a second heat exchanger in such a manner that accumulation of water by condensation on the cooler side of the circuit may compensate in part for water lost on the warmer side of the circuit.

Other objects and advantages of my invention will be apparent in the following detailed de-

scription considered with the accompanying drawings.

In the drawings:

Fig. 1 is a vertical cross-sectional view largely diagrammatic of my invention embodied in an air conditioning unit of a portable or semi-portable type.

Fig. 2 represents a flow chart for the circulation of the heat-transfer medium when the apparatus is functioning to cool the indoor air.

Fig. 3 is a similar flow chart indicating the movement of the heat-transfer medium in the course of heating the indoor air by mechanical action.

Fig. 4 is a similar chart indicating the circulation of the medium when an auxiliary burner is in operation for heating by fuel consumption in extremely cold weather.

Fig. 5 is a diagrammatic view similar to Fig. 1 showing the principles of my invention incorporated in a multiple-unit apparatus for affecting indoor air at a plurality of points.

Fig. 6 shows schematically an arrangement for simultaneous control of a plurality of valves in one of my systems.

Fig. 7 is a sectional view indicating one modification of my invention.

Fig. 1 shows a room having a floor 10 and an exterior wall 11. An air conditioning unit, enclosed by a suitable casing 12, includes a duct 13 for circulating a stream of outdoor air through the unit, the duct comprising an intake portion 14 extending through the wall 11, and a discharge portion 15 likewise extending through the wall 11. It will be obvious to those skilled in the art that operating conditions may be satisfied by merely extending duct portions 14 and 15 through a window or transom. In the interior of the unit the duct 13 is enlarged to provide a suitable chamber 18 for housing a heat exchanger 19. A vertical set of louvres 20 are provided on the downstream side of the heat exchanger compartment 18 and inclined for drainage towards the interior of the compartment, the bottom 21 of the compartment being formed as a pan to receive such drainage.

Blower means, such as a fan 22 driven by an individual motor 23, is provided for forcing circulation of outdoor air through the duct 13. The air conditioning unit also incorporates a duct 26 for indoor air, including an intake portion 27, a discharge portion 28, and an intermediate chamber 29 for a second heat exchanger 30. Preferably, as previously described, the second chamber will also be provided with a set of louvres 31 and will have its bottom 32 formed as a pan.

A blower for forcing a stream of indoor air through the duct 26 may comprise a fan 33 driven by an individual motor 34. Since the two ducts 13 and 26 will ordinarily differ considerably in temperature, an intervening partition 41 of heat insulating material is desirable.

The outdoor heat exchanger 19 may be of a well known construction, comprising an upper header 42 communicating with a pipe 43 and a lower header 44 communicating with a pipe 45, the two headers being interconnected by suitable tubes 46 having fins 47. A separator 48 is associated with the pipe 43 adjacent the upper header 42 for the purpose of entraining any liquid that may tend to flow out of the header into the pipe, the liquid draining towards the lower header 44 through a suitable drain pipe 49.

The heat exchanger 30 for the indoor air is of similar construction, comprising an upper

header 50 communicating with a pipe 51 and a lower header 52 communicating with a pipe 53, the two headers being interconnected by a plurality of tubes 54 having fins 55. This second heat exchanger is likewise provided with a separator 56 associated with the upper header 50, the separator having a drain pipe 57 leading to the lower header 52.

A motor 39 actuates a compressor 58 for the heat-transfer medium, the operative interconnections including a sheave 59 on the motor shaft 40, a sheave 60 on a compressor shaft 61, and a belt 62 interconnecting the two sheaves.

From the discharge side of the compressor 58 a pipe 63 controlled by a valve 64 communicates with the previously mentioned pipe 43 associated with the upper heat exchanger 19, and a second pipe 65 controlled by a valve 66 communicates with the pipe 51 associated with the lower heat exchanger 30. In similar manner, from the intake side of the compressor 58 a pipe 67 controlled by a valve 68 communicates with the pipe 43 associated with the upper heat exchanger, and a second pipe 69 controlled by a valve 70 communicates with the pipe 51 associated with the lower heat exchanger 30. It will be apparent that in such an arrangement the valves may be manipulated to cause the compressor to pump the heat-transfer medium from either heat exchanger to the other.

The closed circuit for the heat-transfer medium is completed by a fluid receiver or reservoir 71 with which pipes 45 and 53 communicate, the pipes having valves 72 and 73 respectively adjacent the reservoir. Extending downward into the liquid body within the reservoir 71 is a discharge pipe 74, the lower end of which has a valve 75 controlled by a float 76. The upper end of the discharge pipe 74 has two branches, one branch 77 controlled by a valve 78 leading to the pipe 45 above the valve 72 and the other branch 79 controlled by a valve 80 leading to the pipe 53 above the valve 73.

In installations where an auxiliary combustion means may be desirable, I incorporate in my apparatus a boiler 81, preferably associated with the reservoir 71. As shown in the drawings, the boiler may have an upper pipe 82 connected with the reservoir 71, and a second pipe 83 disposed to drain from the bottom of the reservoir. From the top of the boiler a pipe 84 controlled by a valve 85 communicates with the pipe 51 associated with the lower heat exchanger 30. A suitable burner 86 having a fuel pipe 87 is shown positioned at the lower end of the boiler.

Since heat is generated both by the motor 39 and the compressor 58, both may be enclosed by an inner casing 88 adapted to be vented to one or both of the air ducts. Thus, an intake vent pipe 89 controlled by a butterfly valve 90 extends from the intake portion 14 of the duct 13 to the inner casing 88, the intake end of the vent pipe being directed upstream, as shown, and a discharge vent pipe 91 controlled by a butterfly valve 92 extends from the inner casing 88 to the discharge portion 15 of the air duct 13, the discharge end of the vent pipe being directed downstream, as shown. In similar manner an intake vent pipe 93 controlled by a butterfly valve 94 and a discharge vent pipe 95 controlled by a butterfly valve 96 interconnect the inner casing 88 and the duct 26. By manipulation of the various butterfly valves, the inner casing 88 may be vented to the outdoor air when the unit is operating to cool the indoor air, and the casing may

be vented to the indoor air during the seasons when the apparatus is employed to heat the indoor air.

For the heat-transfer medium, any of the well known refrigerants may be provided, such as ethyl chloride, methyl chloride, ammonia, the fluid known to the trade as Freon, and the like. A sufficient quantity of the heat-transfer fluid is introduced into the system to fill to the desired point whichever heat exchanger is functioning as an evaporator, sufficient liquid being retained automatically in the reservoir 71 to seal the lower end of the pipe 74. The heat-transfer medium in liquid state drains into the reservoir 71 from the heat exchanger that functions as a condenser, and as the liquid in the reservoir tends to rise above a level governed by the adjustment of the float 76, the liquid is released through the pipe 74 to flow into the heat exchanger that is functioning as an evaporator.

When it is desired to have the air conditioning apparatus operate to cool the indoor air, the various valves are adjusted to provide the closed circuit indicated diagrammatically by full lines in Fig. 2. In this circuit the heat-transfer medium in gaseous state is put under pressure by the compressor 58 and transmitted through the pipe 63, the valve 64, and the pipe 43 to the heat exchanger 19 associated with the stream of outdoor air. The temperature of the medium is lowered in the heat exchanger 19 and the resulting condensate drains through the pipe 45 and the valve 72 into the reservoir 71. From the reservoir 71 liquid under pressure is released through the pipe 74 to pass through the pipe 79, the valve 80, and the pipe 53 into the lower header 52 of the heat exchanger 30, in which heat exchanger the liquid evaporates and takes up heat from the surrounding air stream. From the heat exchanger 30, the vaporized medium returns to the intake side of the compressor through the pipes 51 and 69. It is apparent that in this mode of operation, the apparatus, in effect, pumps heat from the stream of indoor air in the duct 26 to the stream of outdoor air in the duct 13.

When it is desired to raise the temperature of the indoor body of air with respect to the outdoor atmosphere, the various valves are adjusted to provide a closed circuit in the reverse direction, as indicated diagrammatically by the full lines in Fig. 3. The heat-transfer medium in gaseous state is compressed by the compressor 58 and delivered to the heat exchanger 30 through the pipe 65, the valve 66, and the pipe 51. Within the heat exchanger 30 the medium changes to the liquid state giving up its latent heat of vaporization to the surrounding air stream. The liquid drains from the lower header 52 of the heat exchanger through the pipe 53 and the valve 73 to the reservoir 71, and from the reservoir flows upward to the heat exchanger 19 through the pipe 74, the pipe 77, the valve 78, and the pipe 45. Within the upper heat exchanger 19 to the liquefied heat-transfer medium is vaporized, taking its heat of vaporization from the surrounding air stream. The cycle is completed by the vaporized medium passing to the intake side of the compressor 58, through the pipe 43, the pipe 67, and the valve 68. In this cycle, it is evident that the apparatus pumps heat from the outdoor air stream to the indoor air stream.

I have reason to believe from my tests that when the outside air averages 40° F. to 50° F. and the room is held at a temperature of 80° F., a kilowatt hour of energy consumed in driving the

apparatus will transfer a total of between 10,000 and 15,000 B. t. u., which is three or four times the amount of heat produced by passing the same current through a resistance element.

- 5 When, in cold weather, the difference between the outdoor temperature and the indoor temperature is too large for satisfactory heating by the cycle indicated by Fig. 3, all the motors except the motor 34 driving the fan 33 are shut down, 10 the various valves of the system are manipulated to provide the cycle shown in Fig. 4, and the burner 86 under the boiler 81 is ignited. The heat-transfer medium warmed and vaporized in the boiler 81 will pass upwardly through 15 the pipes 84 and 51 to the heat exchanger 30, where the cooling effect of the driven air stream from the room will cause the vaporized medium to liquefy, the latent heat of vaporization being transferred to the room atmosphere. The liquefied medium is drained from the heat exchanger 30 through the pipe 53 and the valve 73 to the receiver 71, where it is permitted to return to the boiler through the lower pipe 83 or the upper pipe 82.
- 25 One of the features of my invention is the provision of means for wetting the surfaces of at least one of the heat exchangers in the system. Preferably such an arrangement will be extended to all of the heat exchangers involved. 30 In Fig. 1 the reservoir means, generally designated by the numeral 99 is enclosed by a relatively heavy casing 100 of heat-insulating material. One tank for supplying both of the heat exchangers may be employed, but I prefer, for reasons that will become apparent, to provide two separate tanks, one tank 101 for liquid to spray the heat exchanger 19, and a second tank 102 for liquid to spray the heat exchanger 30. The advantage of employing one reservoir for both heat exchangers is that increments of liquid condensed at one heat exchanger returning to the common reservoir will offset, at least in part, decrements of liquid lost by vaporization at the other heat exchanger. The advantage of employing two separate tanks is that a desirable temperature difference between the liquids employed for the two heat exchangers may be maintained.

I achieve the advantages of both these alternatives by employing two separate tanks, but spacing the tanks apart, interposing a heat insulating wall 103, and connecting the tanks by a pipe 104 of small diameter extending through the wall. By virtue of this arrangement liquid may be readily equalized between the two tanks with minimum transference of heat. To insure an adequate quantity of liquid for the spray system, one of the tanks, for example, tank 102, may be provided with a water supply pipe 105 controlled by a suitable float valve 106; and to keep the spray system from being flooded, a suitable overflow pipe 107 may extend into one of the tanks.

Liquid passes from the bottom of the tank 101 through a pipe 108 to a pump 109 from which it is delivered through a pipe 110 to a spray nozzle 111, the spray nozzle being directed toward the heat exchanger 19 on the upstream side thereof in the air duct 13. Liquid gathering in the pan 21 below the heat exchanger 19 drains back into the tank 101 through a suitable drain pipe 112. In like manner, liquid from the tank 102 passes through a pipe 113 to a pump 114 and then through a pipe 115 to a nozzle 116 directed against the heat exchanger 30, and the liquid from the pan 32 below the heat exchanger

returns to the tank 102 through a suitable pipe 117.

The two pumps 109 and 114 have a common shaft 118 driven by the motor 39 through the medium of sheaves 119 and a belt 120.

Fig. 5 indicates how the principles of my invention may be embodied in a multiple-unit system in which a central exchanger 123 associated with the outdoor air is balanced with a plurality of dispersed secondary heat exchangers such as typified by secondary heat exchangers 124 and 125 associated with indoor air.

The central air conditioning unit of the system is housed in a suitable casing 126 providing an air duct 127 for the circulation of outdoor air, the air being driven by a suitable fan 128 that is operatively connected with a motor 129 by means including a belt 130. The air duct 127 is shaped to provide a suitable drainage pan 131 for spray liquid, and is provided with a set of louvres 132 disposed to drain liquid into the pan. A pipe 133 communicates with the upper header 134 of the heat exchanger 123, and a second pipe 135 is connected with the lower header 136 of the heat exchanger, the usual separator 137 being associated with the pipe 133 to drain to the lower header through a pipe 138.

The pipe 135 connects with a pipe 139 above a valve 140, the pipe 139 at its lower end draining into a receiver or reservoir 141 for the heat-transfer medium employed in the system. The upper end of the pipe 139 connects with a tank 142 that may be employed to control the liquid level in the heat exchanger 123 when that heat exchanger is functioning as an evaporator. Within the tank 142 the upper end of an intake pipe 143 is controlled by a float valve 144. The pipe 143 terminates at its lower end in the receiver 141 near the bottom thereof, and is controlled by a suitable valve 145.

The secondary heat exchanger 124 is part of a secondary air conditioning unit housed in a casing 146, the casing being provided with an air duct 147 through which indoor air is propelled by a fan 148. The fan 148 is driven by a motor 149 through means including a belt 150. The air duct 147 is formed with a drainage pan 151 below the heat exchanger 124 and is provided with sets of louvres 152.

The upper header 153 of the heat exchanger 124 communicates with a pipe 154 and the usual separator 155, the separator draining to the lower header 156 through a suitable pipe 157. The lower header 156 has a pipe 158 that connects with a second pipe 159 above a valve 160. The upper end of the pipe 159 is connected with the bottom of a tank 161 that may be employed to control the liquid level in the heat exchanger 124. The lower end of the pipe 159 connects with a pipe 162 that connects in turn with the previously mentioned pipe 139 to provide flow back to the receiver 141. Within the tank 161 an intake pipe 163 is controlled by a float valve 164. Below the tank 161 the intake pipe 163 is controlled by a valve 165 and connects with a pipe 166 that connects in turn with the pipe 143 below the valve 145.

The second auxiliary air conditioning unit in the system incorporating the heat exchanger 125 is similar in construction to the unit just described. The second auxiliary unit is housed by a casing 167 that provides an air duct 168 through which indoor air is driven by a fan 169. The fan 169 is driven by a motor 170 through means including a belt 171. The air duct pro-

vides a drainage pan 172 and the usual set of louvres 173. A pipe 174 connects with the upper header 175 of the heat exchanger, and the usual separator 176 associated with the pipe 174 drains to the lower header 177 of the louvres through a suitable pipe 178. The lower header 177 of the heat exchanger has a pipe 179 that connects with a second pipe 180 above a valve 181, the pipe 180 in turn connecting with the aforementioned pipe 162 that leads to the receiver 141. The upper end of the pipe 180 connects with a tank 182 having an intake pipe 183 controlled by a float valve 184. The intake pipe 183 has a valve 185 below the tank 182, and leads to the previously mentioned pipe 166.

It is to be understood that, by preference, the central unit of the system incorporating the heat exchanger 123 will be located at a much lower level than the auxiliary air conditioning units incorporating the heat exchangers 124 and 125, so that drainage from the auxiliary units to the central unit will be simplified. For example, the central air conditioning unit may be below the first floor level of a building. In any installation where the central unit must be higher than the auxiliary unit, it will be within the skill of an ordinary mechanic to provide pumps or other means for the required circulation of the heat-transfer medium.

The compressor 187 for the heat-transfer medium is driven by the motor 129 through means including a belt 188. The discharge pipe 189 of the compressor has two branches, one branch 190 controlled by a valve 191, and a second branch 192 connecting with the pipes 154 and 174 that lead to the upper headers, respectively, of the heat exchangers 124 and 125. To cut off flow through the branch 192, a valve 193 is provided in the pipe 154, and a valve 194 in the pipe 174. The branch pipe 190 is connected with the pipe 133 through a short pipe 195, there being a valve 197 in the pipe 133 near the point of connection.

The intake pipe 198 of the compressor likewise has two branches, one branch 199, controlled by a valve 200, connecting with the pipe 195, the other branch 201 communicating with two pipes 202 and 203. The pipe 202 controlled by a valve 204 connects with the pipe 154 on the side of the valve 193 towards the heat exchanger 124, and the pipe 203, controlled by a valve 205, connects with the pipe 174 on the side of the valve 194 towards the heat exchanger 125.

In the central air conditioning unit, a boiler 206 having a burner 207 is connected with the receiver 141 through an upper pipe 208 and a lower pipe 209, the lower pipe connecting with the bottom of the receiver. The pipe 210 from the top of the boiler 206 has a valve 196 and connects with the pipe 195. The fuel pipe 211 to the burner 207 is controlled by a pressure-responsive valve 212 having a pipe 213 to transmit pressure from the boiler 206.

When the system is employed to cool the indoor air, only the following valves are open: valves 191, 197, 140, 165, 204, 185, and 205. From the compressor 187 the vaporized heat-transfer medium flows through the pipes 189, 190, 195, and 133, to the heat exchanger 123, in which the heat-transfer medium liquefies and then drains through pipes 135 and 139 to the receiver 141. From the receiver 141, the liquefied heat-transfer medium flows through the pipe 166 to the two secondary heat exchangers, the path to the heat exchanger 124 being through the pipe 163, the

tank 161, and the pipes 159 and 158, and the path to the heat exchanger 125 being through the pipe 183, the tank 182, and the pipes 180 and 179. In the two secondary heat exchangers the heat-transfer medium is vaporized in the usual manner, and the vapors are drawn back to the compressor 187, the flow from the heat exchanger 124 being through the pipes 154 and 202 to the pipe 201, and the return flow from the heat exchanger 125 being through the pipes 174 and 203 to the pipe 201.

When the system functions to transfer heat from the outdoor air to the indoor air, only the following valves are open: valves 193, 160, 194, 181, 145, 197, and 200. From the discharge side of the compressor 187, the vaporized heat-transfer medium is delivered to the two secondary heat exchangers through the pipes 189, 192, 154, and 174. In the two secondary heat exchangers the heat-transfer medium is liquefied, yielding up its latent heat of vaporization, and the liquid drains back to the receiver 141 in the central unit, the return from the heat exchanger 124 being through the pipes 158 and 159 to the pipe 162, and the return flow from the heat exchanger 125 being through the pipes 179 and 180 to the pipe 162.

When the boiler 206 is in operation for providing heat in colder weather, only the following valves are open: valves 196, 191, 193, 160, 194, and 181. The vaporized heat-transfer medium passes from the boiler 206 through the pipes 210, 133, 195, 190, and 192, branching to the heat exchanger 124 through the pipe 154 and to the heat exchanger 125 through the pipe 174. In the secondary heat exchangers the medium liquefies, yielding its heat of vaporization, and the liquid flows back to the receiver 141, the return flow from the heat exchanger 124 being through the pipes 158 and 159 to the pipe 162, and the return flow from the heat exchanger 125 being through the pipes 179 and 180 to the pipe 162. From the receiver 141 the liquid returns to the boiler 206 through the pipe 209. The temperature of the boiler is maintained by the action of the pressure-responsive valve 212.

In the multiple unit embodiment of my invention, as in the single unit embodiment previously described, I prefer to incorporate means for wetting the various heat exchangers. The central air conditioning unit includes a spray tank 215 having a supply pipe 216 controlled by a float valve 217 and a suitable overflow pipe 218. Liquid from the spray tank 215 passes through a pipe 219 to a spray pump 220 from which it is delivered through a pipe 221 to a nozzle 222 directed toward the heat exchanger 123, the pump being actuated by the motor 129 through suitable means including a belt 223. The liquid dripping from the heat exchanger 123 and the louvers 132 collects in the pan 131 and drains through a pipe 224 back to the tank 215.

The liquid for spraying the heat exchanger 124 may conveniently be held in reserve in the drainage pan 151, and, in the same manner, the liquid for spraying the heat exchanger 125 may be held by the drip pan 172. To insure an adequate supply of such liquid, a pipe 225 branches from the pipe 221 on the discharge side of the pump 220, the pipe 225 having one branch 226 extending into the pan 151 and controlled by a float valve 227 and a second branch 228 extending into the drip pan 172 and controlled by a float valve 229. To keep the two drip pans from being flooded, an overflow pipe 230 from

the drip pan 151 and a second overflow pipe 231 from the drip pan 172 join at a pipe 232 that drains into the tank 215 in the central air conditioning unit.

5 In the spraying of the heat exchanger 124, liquid from the pan 151 passes through a pipe 233 into a pump 234 and then is delivered through a pipe 235 to a spray nozzle 236, the pump being driven by the motor 149 through suitable means including a belt 237. In like manner, liquid from the drip pan 172 circulates through a pipe 238, a pump 239, and a pipe 240 to a spray nozzle 241, the pump being driven by the motor 170 through a belt 242.

15 Whenever the spray system gains water by condensation at the two secondary heat exchangers 124 and 125, the excess water drains back through the overflow pipes 230 and 231 to the tank 215 in the central unit. If the water added to the contents of the tank 215 over-compensates for loss of spray liquid by evaporation in the air duct 127, the excess liquid will drain away through the pipe 218; but if the added liquid is insufficient to offset such losses by evaporation, fresh liquid will be automatically introduced through the pipe 216 by automatic operation of the float valve 217. On the other hand, if water is being lost from the spray system in the air ducts 147 and 168, replacement will be had automatically through the pipe 225 and its branches 226 and 228. If an insufficient quantity of moisture is condensed in the air duct 127 to compensate for flow through the pipe 225, additional water will be introduced into the system automatically through the pipe 216 by operation of the float valve 217. If the condensation in the air duct 127 over-compensates for the fluid loss in the secondary units, the excess will flow away through the drain pipe 218.

20 The advantages of the spraying operation will be discussed first in relation to an indoor heat exchanger functioning as an evaporator to cool the air. The liquid being discharged from the spray nozzle is relatively cool because of its previous contact with the heat exchanger, and this relatively cool liquid traversing the space between the nozzle and the heat exchanger in the form of spray droplets rapidly absorbs heat from the air. Upon reaching the heat exchanger, the 25 spray droplets, under the action of the relatively strong air currents, repeatedly impinge against the fin and tube surfaces of the heat exchanger. Each time a particle of liquid touches a metal surface, which metal is here of relatively low temperature, it loses heat, and each time it is swept off the surface into the relatively warm air stream it absorbs heat. Since the solution is divided into myriad small particles having an immense aggregate surface, and since these particles alternate rapidly between the air stream and the metal surfaces before they finally reach the drip pan under the heat exchanger, the transfer of heat from the air stream to the heat exchanger is exceptionally rapid and efficient.

30 The spraying operation also serves to wash the air stream by entrapping particles of dust, and I prefer additionally to achieve sterilization by adding a suitable germicidal agent to the spray liquid.

35 An important feature of my invention is that by employing an aqueous solution of some non-volatile compound, instead of plain water, for spraying the heat exchangers, I may achieve new functions and new advantages. A solution of an inorganic salt, for example, and certain

organic substances highly soluble in or miscible with water are suitable for my purpose. A sodium chloride, or calcium chloride brine, or some non-volatile organic solute such as glycerine may be employed. The first of these new advantages is the prevention of frost formation when the solution is continuously sprayed over a heat exchanger that is functioning as an evaporator. Since the more concentrated the solution the lower its freezing point, I may select a concentration to prevent the formation of frost at temperatures even lower than 0° F.

When the indoor heat exchanger is functioning as a condenser in a cycle for heating the indoor air, the spraying operation will facilitate the transfer of heat from the surface of the heat exchanger to the ambient air, the liquid taking up heat when in contact with the surfaces of the heat exchanger and losing heat when being wafted by the air stream from one metal surface to another. When the apparatus is being operated on the heating cycle, the indoor sprays will, of course, wash the air as before described, and, again, a germicidal agent may be added to the liquid.

An important function of a brine or other chemical solution used as a spray for an indoor heat exchanger is to regulate the humidity of the indoor body of air to an effective extent. The salts mentioned and other well known compounds in aqueous solution will maintain a water-vapor tension well below that of pure water at the same temperature. If a saturated or near saturated air stream is exposed to such a solution, water vapor will be drawn from the air, there being a tendency for equalization of the two vapor tensions. On the other hand, if the air stream is extremely dry, it will derive vapor content from the spray solution. Thus, in summer time when the heat exchanger is being employed as an evaporator to cool the air stream, there will ordinarily be a distinct tendency for the spray solution to de-humidify the saturated air to a desirable extent. On the other hand, in winter time when the indoor heat exchanger is functioning as a condenser, the opposite tendency occurs, because in winter time the air is usually well below its dew point before heating so that increase in temperature makes the air extremely dry. The spray solution will not, of course, permit the current of air to attain a relative humidity of 100% because its vapor tension is below that of ordinary water, but it will definitely serve to increase the relative humidity of the air and cause the occupants of a room to feel comfortable at a lower temperature than otherwise. The more soluble the salt or other chemical employed and the higher its ionization, the lower the vapor tension. It is apparent, then, that by controlling the concentration of the solution in the spray system, I may control the humidity of the indoor air to a desirable extent.

I have previously pointed out that the provision for equalization between the body of liquid employed for a heat exchanger associated with the indoor air and the body of liquid employed for spraying a heat exchanger associated with the outdoor air permits water gained by condensation on one side of the spray system to be transferred to the other side of the spray system to compensate for water loss by evaporation. It is to be noted that, in effect, I have provided means for replenishing the solution with distilled water, thereby avoiding the excessive introduction of

minerals into the liquid as would result from replenishment with ordinary tap water.

A refinement of my system consists in the introduction of a novel principle of temperature control in which the effectiveness of the compressor is arranged to be responsive to the pressure of the heat-transfer medium in the indoor heat exchanger. The effectiveness of this type of control is based on the fact that the boiling temperature of a liquid is determined by the pressure.

As an example of an arrangement for such temperature control, I show conventionally in Fig. 5 a device 243 associated with the compressor 187 for regulating the displacement per stroke of the compressor by means of clearance pockets in a manner familiar to those skilled in the art. The displacement-regulator 243 is adjustably responsive to pressure transmitted thereto through a pipe 244. The pipe 244 has two branches: one branch 245, having a valve 246, leads to the pipe 201 associated with the intake side of the compressor; the other branch 247, having a valve 248, leads to the pipe 192 associated with the discharge side of the compressor. By manipulation of the valves 246 and 248, the displacement-regulator 243 may be made responsive to the pressure in the secondary heat exchangers 124 and 125 when those heat exchangers are serving as evaporators, as well as when those heat exchangers are serving as condensers for the heat-transfer medium. When, in the course of heating the indoor air, the secondary heat exchangers are employed as condensers, the displacement-regulator will be adjusted to respond to a drop in pressure by increasing the capacity of the compressor. On the other hand, when the secondary heat exchangers are employed in a cycle for cooling the indoor air, the displacement-regulator will be adjusted to increase the capacity of the compressor when the pressure in the secondary heat exchangers rises above a predetermined value. In either case the regulator is connected to oppose any deviations of pressure from a desired value whether up or down.

The described arrangement for temperature regulation provides automatically for varying the load on the motor of the central unit and permits operation at maximum efficiency without the necessity of constant attention to the mechanism of the central unit. For further control of the temperature of the indoor body of air, the motors associated with the secondary unit may be controlled in speed by manual means or by room thermostats in a well known manner. One advantage of the arrangement for temperature regulation just described is that it supplies a basis for determining fan capacity, amount of chemical circulated, and amount of exchanger surface required to effect the desired heat exchange between the heat-transfer medium and the indoor body of air at a given room temperature.

In each of the forms of my invention it is necessary to manipulate several valves to reverse the cycle of the heat-transfer medium. It is contemplated that all the valves involved in such reversal will be operated simultaneously by some convenient manual means. For example, in the apparatus shown in Fig. 1, eight valves control the circulation of the heat-transfer medium, four of which are turned off and four turned on to reverse the cycle. A construction that may be

employed for the simultaneous control of all of the valves is shown in Fig. 6.

In Fig. 6, the eight reversing valves of Fig. 1 are shown mounted in a frame 245, the valves 64 and 70 having a common valve stem 246, the valves 66 and 68 having a common valve stem 247, the valves 72 and 80 having a common valve stem 248, and the valves 73 and 78 having a common valve stem 249. Journalized centrally in the frame 245 is a shaft 250 controlled by an external crank 251. Keyed to this shaft are two pinions 252, each of which operatively engages a pair of pinions 253. Each of the pinions 253 controls one of the four dual valve stems. When the crank 251 is rotated in one direction, it closes the valves 64, 70, 72, and 80, and opens the valves 66, 68, 73, and 78. Rotation of the crank in the opposite direction has the opposite effect.

In a multiple-unit system such as shown in Fig. 5, it is advantageous to have the fans of the secondary units controlled by room thermostats. Thus, the fan motors 149 and 170 may each be controlled through wires 254 by a room thermostatic switch 255. Preferably, a manual switch 256 will also be included in the control circuit. When, for example, the secondary units are being heated by vapors generated in the central boiler 206, each of the fans in the secondary unit will normally be energized and de-energized automatically in accordance with temperature conditions. By opening the manual switch 256 associated with a given secondary unit, the secondary unit may be made inoperative for economy where, for example, one of the rooms of a building is not being used.

In one of the forms of my invention I surround the receiver or reservoir for the heat-transfer medium with a relatively large body of liquid for storing heat. For example, instead of using the simple tank 141 shown in Fig. 5, I may employ a tank 257 having exterior fins 258, as shown in Fig. 7. This tank is encased by a relatively large and heavily insulated tank 259 that is substantially filled by a body of water 260. As relatively hot liquid is continuously entering the tank 257 in the normal operation of my apparatus, heat is transferred to the enveloping body of water 260 which will eventually approach the temperature of the liquid in the inner tank. An advantage of this arrangement is that after the compressor is shut down, the heat-transfer medium in the tank 257 will be kept at elevated temperature and will be caused to boil by pressure drop in the system. In this manner the system will tend to function for a substantial period after it is shut down mechanically.

The description and specific arrangements of my invention, set forth herein for the purpose of disclosure and illustration, suggest a wide range of modification and substitution without departing from the principles of the invention. I specifically reserve the right to all such changes and substitutions that come within the scope of my appended claims.

I claim as my invention:

1. An air conditioning apparatus of the character described, including: a first heat exchanger exposed to a stream of outdoor air; a second heat exchanger exposed to a stream of indoor air; means for causing one of said heat exchangers to cool and the other to heat; a reservoir containing an aqueous solution of a non-volatile substance, the solution having substantially lower vapor tension than pure water, said reservoir being

adapted to receive solution drained from the exterior surfaces of said first heat exchanger; a second reservoir containing similar aqueous solution, said second reservoir being adapted to receive solution drained from the exterior surfaces of said second heat exchanger; means to spray said solution against the exterior surfaces of said first heat exchanger; means to spray said solution against the exterior surfaces of said second heat exchanger for controlling the humidity of said indoor air stream, said two reservoirs being interconnected whereby water gained by condensation of moisture from the air at one of said heat exchangers will compensate at least in part for water lost by evaporation at the other heat exchanger; an inlet pipe connected with one of said reservoirs to add water thereto in further compensation for water lost from the liquid by evaporation whereby the total volume of the solution is maintained and whereby the concentration of said non-volatile material in the water is prevented from increasing; and an automatic valve controlling discharge from said inlet pipe in accordance with the liquid level in said reservoir.

2. A reversible air conditioning system including: a first heat exchanger exposed to indoor air and adapted to function as an evaporator for a heat-transfer medium to cool said air or alternatively to function as a condenser to heat said air; a second heat exchanger exposed to outdoor air to impart heat to said outdoor air by functioning as a condenser for said medium when said first heat exchanger is an evaporator and to derive heat from said outdoor air by functioning as an evaporator for said medium when said first heat exchanger functions as a condenser; a reservoir containing a solution of substantially non-volatile material and water, said solution having a vapor tension less than that of water alone and having a freezing point substantially less than 32° F., the surface of said first heat exchanger draining into said reservoir; means including pressure means to spray said solution against said first heat exchanger for controlling the humidity of said indoor air and for preventing frost formation on the heat exchanger when said first heat exchanger functions as an evaporator; a second reservoir containing a solution of the same ingredients, the exterior surfaces of said second heat exchanger draining into said second reservoir; means including pressure means to spray said solution against said second heat exchanger for preventing frost formation thereon when the second heat exchanger functions as an evaporator and to evaporate water from said solution when the second heat exchanger functions as a condenser; means providing a fluid passage between said reservoirs whereby water lost from the solution at the first heat exchanger is at least partially replaced by moisture condensed from the air at the second heat exchanger, and, when the system is reversed, water lost from the solution at the second heat exchanger is at least partially replaced by moisture condensed at the first heat exchanger; and automatic means to replenish said solution with water whenever the total volume of the solution in the two reservoirs drops to a predetermined extent.

3. In an air conditioning apparatus including a first heat exchanger exposed to a stream of outdoor air, a second heat exchanger exposed to a stream of indoor air, and means for causing one heat exchanger to cool and the other to heat, the combination therewith of: a first body of

aqueous solution of a non-volatile substance, the solution having substantially lower vapor tension than pure water; means to spray liquid from said body against the exterior surfaces of said first heat exchanger and to drain the liquid so sprayed back to said body; a second body of a like aqueous solution; means to spray liquid from said second body against the exterior surfaces of said second heat exchanger and to drain the liquid so sprayed back to said second body, thereby controlling the humidity of said indoor air stream; and walls forming an equalization passage between said two bodies whereby water gained by condensation of moisture from the air at one of said heat exchangers will compensate at least in part for water lost by evaporation in the other heat exchanger.

4. A method of operating an air conditioning apparatus of the character described including a first heat exchanger exposed to a stream of outdoor air and a second heat exchanger exposed to a stream of indoor air and wherein one heat ex-

changer acts as a cooler and the other acts as a heater, said method comprising: providing a first body of an aqueous solution of non-volatile substance, the solution having substantially lower vapor tension than pure water; spraying liquid from said body on the exterior surfaces of said first heat exchanger; returning sprayed liquid drained from said first heat exchanger to said body; providing a second body of like aqueous solution; spraying liquid from said second body on the exterior surfaces of said second heat exchanger for controlling the humidity of said indoor air stream; returning sprayed liquid drained from said second heat exchanger to said second body of liquid; and draining liquid from one of said bodies to the other of said bodies whereby water gained by condensation of moisture from the air at one of said heat exchangers will compensate at least in part for water lost by evaporation at the other heat exchanger.

MARION F. KNOY.
